TYPEWRITING-MACHINE.

1,350,681.

Specification of Letters Patent. Patented Aug. 24, 1920.

Application filed November 1, 1917. Serial No. 199,757.

To all whom it may concern:

Be it known that we, BURNHAM C. STICKNEY and ARTHUR A. JOHNSON, both citizens of the United States, said STICKNEY residing in Elizabeth, county of Union, and State of New Jersey, and said JOHNSON residing in borough of the Bronx, county of the Bronx, city and State of New York, have invented certain new and useful Improvements in Typewriting-Machines, of which the following is a specification.

This invention relates to the manifolding function of typewriting machines, especially where certain portions of the typed matter are to be omitted from one or more of the carbon copies thereof, as, for example, in the operation of typewriting an invoice where it is desired to make a carbon record of nothing but the name and date and total, omitting the items which appear in full upon the invoice.

A machine made according to the present invention preferably includes means for supporting and feeding an invoice or other outer sheet, and other means for supporting and feeding a statement or other inner sheet, and for moving the inner sheet into position to receive the type impressions that fall upon the outer sheet, and also for moving the inner sheet away from such impression-receiving position, so that the type impressions will fall only upon the outer sheet and be omitted from the inner sheet; this being done by placing two platens one above another or in tandem relation, and moving them broadside alternatively into and out of printing position, and by arranging to have the outer sheet coöperate with either platen; the inner sheet being arranged upon only one of said platens.

In carrying out the present improvements, the necessary compactness of the platen mechanism and other desirable ends are secured by mounting a platen, which is revoluble for line-feeding, and which is designed to carry the inner sheet, above the other platen; said other platen being relatively diminutive in cross-section, and readily disposed in an otherwise unoccupied space that occurs forward of the feed roll which runs upon the under side of the upper platen. Both the lower platen and

said feed roll may lie within the bend of a chute, which may be provided for the introduction of outer sheets (for coöperation with either platen) into the machine, so that said lower platen adds little or nothing to the bulk of the typewriting machine.

This compactness is especially valuable in connection with the provision of a superposed registering or collating-table for securing mechanically the desired registration between the inner and outer sheets, while the sheets are in position to be gripped by their respective feed rolls, which therefore shall be near the table. The inner sheet, which may be a statement, is introduced around the revoluble platen, and thence led up to the registering table, upon which it is laid and impaled, by means of perforations in the sheet, upon one or more registering studs, upon the table. Then the outer sheet is introduced into the machine into position for coöperation with either platen, and led up to the registering table and there registered. Before being released from the registering pins, the sheets are clamped by their respective feed rolls, and then they are in position to receive the first line of writing; although in some cases they may first be retracted a given number of line-spaces preparatory to the typing operation; but they retain their relative positions. Other registering or collating means may be employed.

It is the custom to withdraw both invoice and statement sheet from the machine, mailing the invoice to the customer but retaining the statement sheet, so that upon later days it may also receive the carbon records of other invoices; the statement sheet being re-inserted in the machine for each invoice until the end of the month, when it is mailed to the customer. From these statement sheets the items are omitted, said items being typed only upon the invoice sheets. At each re-insertion of the inner or statement sheet, it is necessary to bring it to a different position with relation to the outer or invoice sheet, and this is done readily by using said registering or collating-table, whereby the sheets may be accurately assembled or collated in any desired registration or relationship. Thus,

by the use of a registering or collating-table in conjunction with means for withdrawing the statement from printing position while the items upon the invoice are being written, it becomes feasible to make the invoices, statement and ledger sheet all at the same time, without the necessity of recopying from one to another, and without the necessity of encumbering the statement and ledger sheets with the items, and without difficulty in securing the desired relative positions of the invoice and statement sheets in the machine.

The collating-table, for this purpose, is placed just over the platens, but sufficiently near to the sheet-clamping devices to enable both the outer and inner sheets to be clamped before they are released from the collating-table. The sheet-feeding or clamping means for the outer sheet comprises a feeding couple arranged at the delivery side of the machine in proximity to the collating-table. The clamp for the inner sheet may comprise a feed roll running upon the under side of the revoluble platen, but not at an excessive distance from the collating-board, since this platen, being the upper one, is in proximity to the collating-board, and since the small size of the lower platen necessitates only a slight upward movement of the platens in order to bring the lower platen to printing position, and hence but little clearance is needed between the upper platen and the collating-table, thus minimizing the extent of sheet between the collating-pins and the feed roll on said upper platen.

For introducing the outer sheets, there is provided a chute arranged at the rear of the platens, and extending downwardly and bending forwardly under the same and upwardly in front thereof to direct the outer sheet upwardly just in front of the platens, and up to the associated feeding couple. The paper-guiding apron for the inner sheet is arranged above said chute, and is directed downwardly and curves upwardly under the revoluble platen to the front thereof.

Line-spacing of the inner and outer sheets may be done by a single stroke of the hand of the operator. The mechanism preferably comprises a single line-spacing handle and trains of mechanism ramifying therefrom to the revoluble platen (which controls the inner sheet) and to the line-feeding couple which controls the outer sheet. The surface speed of the inner and outer sheets may vary. Moreover, each line-spacing train may include an individual line-space regulator, so that variation may be secured by setting the regulators as desired; for example, the outer sheet may be advanced a triple line-space at each operation of the line-spacing handle, as in writing checks and other wide-spaced papers, while the inner sheet may be advanced only a single

line-space, so as to condense the carbon record upon the statement or other record sheet.

An additional record sheet may be retained in position in the machine while the statement sheet and invoice sheet are removed, to preserve carbon copies of all of the names and footings which appear upon the various statement sheets, without including the items that are written in full upon the invoices. Preferably this condensed record sheet feeds around the revoluble platen within the statement and ledger sheets, but is held in place by clips while the statement and ledger sheets are being removed and replaced. Being placed upon said revoluble platen, it receives only the condensed or abridged data that are placed upon the statement and record sheets. In some cases other data may also be placed upon both the invoice and this condensed record sheet, before the statement and ledger sheets are introduced into the machine. Provision is preferably made for automatically advancing the condensed record sheet a line-space after the accumulation of an entry thereon, so as to space the same from the following entry.

The revoluble platen, in moving away from printing position, becomes disconnected from the line-spacing mechanism, so that the sheets thereon will neither be written upon nor line-spaced.

Other features and advantages will hereinafter appear.

In the accompanying drawings,

Figure 1 is a part-sectional plan of the carriage of an Underwood front-strike type-writing machine, modified to disclose the present improvements in one form.

Fig. 2 is a part-sectional front elevation of the carriage and other parts seen in Fig. 1.

Fig. 3 is a sectional side elevation to show the line-spacing mechanisms, including the regulating device for each mechanism.

Fig. 4 is a sectional view to illustrate means for preventing accidental rotation of the revoluble platen when the same is swung up away from printing position and from its connection with its line-space drive wheel; this figure also showing means for automatically providing a line-space between entries upon the condensed record sheet.

Fig. 5 is a detail of one method of withdrawing the registering or collating pins.

Fig. 6 is a diagram to illustrate the arrangement of carbons and inner and outer sheets and condensed record sheet with relation to the revoluble platen.

Fig. 7 is a sectional side elevation to illustrate trains of line-spacing mechanism which ramify from the line-spacing handle to the feeding couples.

Fig. 8 is a sectional side elevation, showing the general arrangement of platens and appurtenances upon the carriage of an Underwood typewriting machine, showing 5 the revoluble platen as down in working position, and the fixed platen as out of working position.

Fig. 9 is a view similar to Fig. 8, but 10 showing the revoluble platen as up out of working position, and the outer sheets as being typed upon the lower platen, which is elevated to working position.

The drawings illustrate the invention in connection with an Underwood typewriting machine, in which a paper-carriage 20 travels upon rails, of which one is shown at 21. The types 22 (which preferably are all upper-case, figure and character types, so that no case-shifting mechanism is required) 15 strike through a ribbon 23 carried by a vibrator 24 as usual. The type impressions may be received upon either of two platens, the upper of which 25 is illustrated as revoluble for line-spacing, and the lower of 20 which 26 need not be; and these platens are connected for movement to bring either one to printing position while the other one is moved away from printing position. For this purpose, both platens are mounted upon 25 a frame which swings about a shaft 27 which is journaled in the vertical sides 28 of the carriage 20. The platens 25 and 26 extend between plates 29 forming the sides of the swinging frame, which is provided with a handle 30 mounted upon an arm 31 extending up from one of the side plates. Said frame may have a pin 32 to engage a notch in a latch 33 to lock the frame elevated, as at Fig. 9, with the upper or revoluble platen 30 away from the printing point and the lower platen brought into use. The latch is provided with a finger-piece 34 for causing it to release the swinging frame, comprising the side plates 29, and a tie-rod 35, mounted on 35 the shaft 27 so that the frame may gravitate to normal position in which the platen 25 is at the printing point, with pin 32 resting against an edge of the carriage plate 28.

Around the revoluble platen 25 may be 40 carried a record sheet 36 and a ledger sheet 37, Fig. 6, or any other assemblage of sheets, for example a statement sheet, a ledger sheet and an intervening carbon. These may be introduced into the machine by inserting 45 them at the rear of the platen 25 and between the same and a paper-shelf or guiding apron 38, Fig. 8, which extends downwardly and forwardly and then curves upwardly toward the front of the platen, to confine 50 the sheets to the platen; and the sheets may be pressed against the platen by feed rolls 39 carried by means of swing arms 40 upon the tie-rod or shaft 35 which connects the side plates 29 of the swinging frame. To 55 permit the sheets to be introduced, between

the platen and feed-roll or rolls 39, the latter may be cast off by means of a release key 41, Fig. 4, which may be connected to a rock shaft 42, having cams 43 to engage release arms 44 on shaft 35.

After the assemblage of sheets 36 and 37 is introduced around the platen and while the feed rolls 39 remain released from the platen, the leading portions of the sheets may be drawn upwardly from the front of the 75 platen and registered upon a board or tablet 45. This registering or collating tablet may be mounted at any suitable place on the delivery side of the typewriting machine, and for convenience is illustrated as overlying 80 the rotary platen 25 and inclining upwardly and rearwardly. For registering or collating purposes, this tablet may be provided with pins 46, and these may be arranged at intervals one above another upon the tablet, 85 to enter holes or perforations usually formed in the side margins of the sheets. After the sheets are thus registered upon the pins, the release key 41 may be manipulated to restore the feed rolls 39 to effective positions to hold 90 the registered or collated sheets upon the platen 25.

While the sheets are thus held, and before any other sheets are introduced into the machine, the types 22 may be operated to write 95 memoranda at the top of the statement, ledger or other sheet.

As soon as the described sheets have been adjusted, or made ready for receiving carbon impressions, the invoice sheet 47 is introduced, together with one or more copy sheets 48, with intervening carbons. This is done while the previously introduced sheets remain stationary in the machine; and these new sheets are inserted at a different point and in rear of the record sheets, and are guided down below the same and then up in front of them, the first set or the record sheets thus occupying positions within the invoice sheet or sheets, as seen at Figs. 100 4 and 6. Preferably the invoice sheets are introduced into a chute comprising a rear inclined wall 49 (which may form a rigid element of the typewriter carriage) and a front wall 50, this chute extending downwardly behind the shafts 27, 35 of the feed rolls 39 on the platen 25, then curving or bending forwardly and upwardly at 51, 51^a, around both the feed roll 39 and the second or fixed platen 26, as the latter lies in its 105 110 abnormal position at Fig. 8.

The upper member 50 of the chute may be bent upwardly and forwardly at its upper end to form a fender 51^b overlying the upper edge of the apron 38 to prevent the 115 120 sheets from being introduced between 50 and 38. Room is made for the upper portion of 38 to turn below or within said fender, as seen at Fig. 9.

The invoice set of sheets is passed readily 130

down through the chute forwardly beneath and upwardly in front of the platen, whence they may be drawn up to pass through a couple of line-feeding rolls 52, 53; the positions of the parts being such that these outer sheets are bent slightly over the platen at the printing point, so that the sheets may be held taut and smooth upon the platen, as at Figs. 8 and 6; the roll 52 and the mouth of the chute 49, 51 being set a trifle back of the extreme front of the platen 25 for this purpose. For convenience in illustrating the work-sheets, the platen 25 is diagrammatically shown undersized. Its real diameter at 52^a, Fig. 8, would be so great as to stand substantially forward of the top 51^a of the chute. The upper roll 53 of the couple is carried upon arms 54. One or more springs 55 cause the roll 53 to bite the roll 52; but by means of a handle 56 projecting from one of the arms 54, Fig. 2, the roll or rolls 53 may be cast off for convenience in introducing the invoice sheets 47, 48, which may be pulled upwardly and by means of the usual perforations either registered or collated upon the pins 46 in any desired relationship with the record sheets 36, 37; whereupon the handle 56 may be manipulated to restore the feed roll 53 to coöperate with the roll 52 to line-feed the invoice set of sheets 47; the feed roll 39 for the revolute platen 25 having been also restored to effective position.

After the feed rolls have been restored, to clamp the sheets where registered, and before any line-feeding is done, the impaling pins 46 may be withdrawn by pressing a handle 57 to the right. This handle is connected to a pair of cam plates 58, Figs. 2 and 8, to engage the pins 46 at the opposite ends of the collating-table 45 to withdraw all of them simultaneously, as at Fig. 9; said cam plates 58 having suitably inclined edges or cams 59 to engage corresponding cutaways or slots 60 in the pins 46 for this purpose, Figs. 2 and 5. The cam plates or rods 58 are connected by cross-bars 61, (the latter may be formed upon a longitudinal slide 62) carrying finger-piece 57. The pins 46 having been withdrawn from the sheets, the line-spacing operations may proceed.

When it is desired to write on the invoice or outer set 47, 48, without writing upon the inner or record set of sheets 36, 37, the platen 25, carrying the latter, is first swung up out of printing position, and the lower platen 26 is simultaneously swung to the printing point, as at Fig. 9. The sheets remain held against the revolute platen 25 by the roll 39, and when limp sheets are used a slight portion thereof above the platen may form a loop or collapse over the platen at 64, Fig. 9, although stiff sheets may ride idly up and down over the tablet 45 as the platen is raised and lowered. The

under platen 26 occupies a position between the side plates 29 of the swing-up frame, and may be fixed relatively to said frame. It will be seen that it is only necessary to swing the handle 30 rearwardly and downwardly in order to bring the small platen 26 into use, as at Fig. 9, so that as many lines as desired may be written upon the outer sheets 47, while the sheets 36, 37 remain stationary upon the cast-off platen 25. Hence, a large number of items may be readily placed upon the invoice sheets 47, 48 without being written upon the record sheet 36 or 37.

This platen 26 may have several faces, each one being flat or slightly arched, and provision may be made for rotating the platen to bring any of these faces into use, to prolong the life of the platen. It may be mounted upon a shaft 66, which is journaled in the side plates 29 of the swing-up frame, and is provided with a finger-piece 67, whereby it may be first released from a locking projection 68 secured to the left-hand plate 29 of the swing-frame and then rotated to bring a fresh face into use, after which a spring 68 may snap the platen back into locking relation with projection 68. Other types of fixed platen may be used, and certain features of the invention are not limited to the use of a fixed platen, at this point. This platen may be compactly placed below the revolute platen 25, occupying but little room between the platen and the chute 50, 51, and may lie within the bend of the outer sheets 47, Fig. 8, and may readily be moved up to a printing position; it being a desideratum to minimize the space between the forward portion of the chute 50, 51 and the collating-table 45, so as to permit relatively short invoices to be collated, while their lower ends remain in said chute. It will be seen that by placing the relatively small platen 26 below the revolute platen 25 of relatively extensive cross-section, not only is desirable compactness attained, but also interference with manipulation of the sheets 37 above the revolute platen 25 is avoided. The small platen 26 is located in proximity to the place where sheets are necessarily confined closely to the large platen 25, and hence are inaccessible, that is, at the under side thereof; said small platen being adjacent to the confining apron 38, so that the small platen 26 may not tend to interfere with the usual manipulation of sheets, the top of the revolute platen 25 being left free for convenience of the operator in manipulating the sheets as usual preparatory to writing thereon. Owing to its small size, the platen 26 may be located just in front of the feed roll 39 on the revolute platen 25, and both 26 and 39 may be confined within the loop or bend which the outer sheets 47, 48 form as

they pass first downwardly at the rear of the machine and then upwardly in front of the platens, so that great compactness of structure is gained, and the necessary convenience of access for manipulating the sheets is preserved.

The chute may be provided at its forward or delivery orifice with light spring fingers 65, to press the invoice sheets against the 10 rear face of the chute, and hold them lightly against accidental displacement, and also cause them to cling closely to whichever platen 25 or 26 may be at the printing point.

15 When it is desired to write the footing, which is to appear upon all the sheets, the latch 33 is released and the platens 25, 26 are swung down with the frame (comprising the plate 29 and tie-rod 35). In other 20 words, the lower platen 26 is moved away from printing position, and the upper platen 25, with the sheets thereon, is brought into printing position, so that said sheets assume printing relation with the invoice 25 sheets 47, as at Figs. 8 and 6, whereby the total amount now written upon the invoice will appear upon all sheets. The record upon the statement and ledger sheets shows merely the name, date and gross amount, 30 omitting the items, saving paper, and avoids the necessity of recopying the amounts from invoices to statements or ledgers. The platen-displacing frame may be limited in its downward movement by a pin 32 on its 35 left-hand plate 29, and a similar pin on its right-hand plate 29; the pins striking edges upon the other plates 28, as shown in Fig. 8.

After the writing of the total upon the invoice and all the remaining sheets, the 40 roll 53 may be cast off and the invoice withdrawn without disturbing any of the remaining sheets; or the entire invoice set of sheets may be withdrawn (while roll 53 is held released by detent 53^a), without disturbing sheets 36, 37. In many cases, however, the sheets 36, 37 will also be withdrawn. A fresh set of sheets 36, 37, and a fresh invoice or invoice set may now be inserted, and the writing proceed as herein- 45 before set forth. The sets 36, 37 are usually preserved and each set is re-inserted in the machine upon successive days, as required, until the end of the month, when the statement sheet 36 is mailed to the customer. At 50 each reinsertion of a set, it may be registered upon the tablet 45, and there remain while the fresh invoice set 47, 48 is also registered or collated in proper position with reference to 36, whereby the operation of 55 invoicing and bookkeeping is expedited. Each fresh invoice is registered in the same position as the last, but at each fresh insertion of the same statement sheet, it is registered or collated in a more advanced position upon the table, whereby skeletonized

carbon copies of successive invoices may follow one another upon the statement.

When a fresh invoice set is to be inserted, the collating pins 46 are first re-projected, and both the outer and inner sets of 70 sheets impaled thereon, to bring the outer sheets 47 into the required relative register with the inner sheets; and then the pins 46 are withdrawn and the operation proceeds as before.

75 It will be seen that a row of the pins 46 extends upwardly at each side of the machine; and it will be understood that while there are only two pins shown in said row, still the row may be extended and have 80 three, or as many more pins therein as may be desired. The advantage of the row of pins extending upwardly along one side of the machine is that they suffice to align and register a sheet which is too narrow to reach 8 over to the row of pins upon the opposite side of the machine; and, hence, certain of these narrow sheets may be impaled upon the left-hand row of pins, and one or more other narrow sheets upon the right-hand 90 row of pins.

It being usually desired to remove the statement and ledger sheet from the machine after the writing of each invoice, (since successive invoices are usually made out to different customers, each having his individual statement and ledger sheet), the statement and ledger sheet in each instance are usually kept clipped together, and are reinserted in the machine daily or at longer 95 intervals during the month. As the statement and ledger sheet gradually fill in this manner, they must at each insertion be collated in proper position to receive the first new line of writing just below the last carbon entry appearing thereon. For this purpose they are usually provided with perforations along their side margins, whereby they may be collated upon the pins 46 by the aid of any suitable mark or scale 70, to 100 indicate where the sheet should be placed, in order that the first line to be written thereon shall follow properly the line written at the last previous insertion.

105 Preferably, the assemblage upon the rev- 115 oluble platen 25, Figs. 8 and 6, comprises a ledger sheet 37, a statement sheet 36 with an intervening carbon, a carbon 72 upon said statement sheet, and a transpicuous tissue sheet 73 facing or overlying the carbon 72, 120 the latter being a double carbon, to make a copy upon the transpicuous facing sheet 73 when the parts are in Fig. 8 position. Because of the provision for copying upon the transpicuous sheet 73, the operator is at any 125 time able to read thereon the entry that has been written upon the statement and ledger sheets. As an aid, the transpicuous sheet 72 may be printed similarly to the statement sheet 36, although it need not be of as great 130

- width as the statement sheet, and need not have the perforated margins. It may be attached at its top to the statement sheet, so that the double carbon may conveniently slip between the two sheets for insertion in the typewriting machine. This assemblage of statement sheet, transpicuous top sheet and double carbon is indicated diagrammatically at Figs. 8 and 6.
- 10 It will be seen that before the invoice set is inserted in the machine, any desired names, memoranda, dates or other items may be written anywhere upon the transpicuous sheet, with ink-ribbon type-impressions, all 15 of which will be visible to the operator; and that then the invoice set may be inserted and written upon, and that a carbon copy of the type impressions will likewise be made upon the transpicuous sheet, as well as upon each 20 of the remaining sheets. This transpicuous sheet, therefore, may be subsequently used as an extra copy of the statement; the transpicuous sheet, the statement and the ledger sheet being preferably clipped together upon being removed from the machine, so as to guard against separation 25 until the next occasion for their use.
- Upon the beginning of the succeeding month, the ledger sheet 37, with its carbon, 30 may first be inserted in the machine, and by means of its side perforations it may be properly located in advanced position upon the pins 46, so that, (after the statement sheet with its transpicuous top sheet and 35 interleaved double carbon have been inserted and collated properly upon said pins 46 relatively to the ledger sheet), the entries made during the writing of invoices in the second month may properly follow the entries made during the first month upon the 40 ledger sheet. This operation may be repeated month after month until the ledger sheet is filled.
- To line-space the outer or invoice sheets 45 (whose special platen 26 is preferably not revolvable for line-spacing), there may be employed a train of mechanism comprising a line-space lever 74, 75, pivoted at 76 as usual upon the main platen frame or carriage 20; the short arm 75 of said lever driving rearwardly a slide 77, which has at its forward end a stud 78, upon which is pivoted a line-spacing drive-pawl 79. This pawl has a tooth 80 that drives a ratchet wheel 81, of the form usually found in an Underwood typewriting machine, and having a spring-pressed detent 82 of ordinary construction. This line-space wheel is fixed upon a stub shaft 83, to the outer end of 50 which may be secured a hand wheel 84, and to the inner end of which is secured a drive gear 85, which, by means of an idle gear 86, rotates a pinion 87 fixed upon the shaft 88 of the roll 52 of the feeding couple which 55 advances the invoices or outer sheets. This roll 52 may comprise several sections; and by means of this feeding couple the outer sheets may be properly line-fed, whether they are being typewritten upon the platen 25 or upon the platen 26.
- The stub shaft 83 preferably occupies the same position as the platen shaft of an Underwood typewriting machine; although in the present instance the axle 89 of the revoluble platen 25 (extending through slot 89^a in platen-frame and carriage-knob 89^b, Fig. 2) is preferably set forward relatively to the shaft or axle 83, because said platen 25 is preferably made of quite smaller diameter than the ordinary Underwood platen, 80 so as to afford room for various new features herein-disclosed and located below, above and in back of said platen.
- The line-spacing of the outer sheets may be regulated by means of a handle 90, corresponding to that in ordinary use in the Underwood machine; its details being well-known, and not needing to be described, as they are substantially the same as in Patent No. 907,632, dated December 22, 1908, to 85 McLaughlin. This handle 90 may be set to three positions for determining whether the invoice or outer sheets shall feed one, two or three line-spaces at each operation of the line-space driving handle 74.
- As it is desirable to be able to line-space the inner or record set of sheets simultaneously with the outer or invoice sheets, as for example in writing the address of the customer upon all the sheets, means are preferably provided for enabling the operator by a single stroke to feed both inner and outer sheets, and this may be accomplished by causing the same line-spaced handle 74 to 90 advance the inner set of sheets simultaneously with the outer set. To this end, a second pawl 91 is pivoted upon said stud 78, with a lateral tooth 92 to drive a ratchet wheel 93, which has a detent 94 and otherwise corresponds with an ordinary Underwood ratchet wheel. This wheel 93, however, is not attached to the stub shaft 83, but is fixed upon a sleeve or hollow shaft 95, Fig. 2, which extends between the wheels 81 and 85; the wheel 93 being upon the outer 95 end of the hollow shaft, and a gear 96 being fixed upon the inner end of the same. Said gear 96, by means of a broad idle pinion 97, drives a gear 98, which also meshes with said pinion 97 and is fixed upon the 100 axle 89 of the revoluble platen 25, so that the surface of 25 advances at the same speed as the outer sheets 47, 48, and hence the latter advance synchronously with the inner sheets 36, 37, at Fig. 8. A separate line-space regulating mechanism 99, which is the same as that usually found upon an Underwood typewriting machine, may be provided for the line-space wheel 93, to permit the operator to determine whether the inner or 105 outer sheets shall be line-spaced.

record sheet shall advance one, two or three line-spaces at each operation of the handle 74.

It will be noted that each line-space regulator may be set independently of the other, and hence that the line-spacing of the inner set and outer set of sheets may be either the same or diverse, since the outer set may have either greater or less line-space intervals than the inner set. This is an advantage where it is desired to have the outer set of sheets written with wide line-spacing, as, for instance, in writing checks or bills, while the inner set advances with narrow line-spaces, to economize the paper upon which the record is preserved.

It will be understood that although both line-space trains will operate when the revolute platen 25 is down in working position, as at Figs. 2 and 7, said platen will not be rotated when it is up out of use, as in the Fig. 9 position, since at that time the platen gear 98 is out of mesh with the pinion 97, which, therefore, rotates idly at such time. In order to avoid rotative displacement of the platen 25 when it is up out of control of the pinion 97, said platen may be provided, as at its right-hand end, with a ratchet wheel 100, Fig. 4, having a pitch suitably corresponding with the pitch of the ratchet wheel 93; and a detent 101 may be provided upon the right-hand side plate 29 of the swing-up frame which carries the platen 25, so as to preserve the rotative position of the platen from the time it is swung up until it is swung down again into the control of its drive pinion 97.

At Figs. 7, 8 and 9, it will be observed that the surface speed of the rotating feed roll 52 is less than that of the revolute platen 25; but it is obvious that the proportions of the gears may be varied, so as to render such surface speeds similar, or such as to render the speed of 25 less than that of 53. Moreover, the speed of line-spacing may be varied by setting the regulators differently; for example, one regulator can be set for single line-spacing while the other is set for triple line-spacing. In some cases both means for effecting variation in the feeding of the inner and outer sheets may be used, that is, the surface speed may be made to vary by means of the gearing, and further variation may be secured by means of the line-space regulators, as in the form of the invention illustrated.

The invention is adapted for a wide variety of purposes, as for further example it can be used for "condensed billing" or check writing, or analogous purposes. The line-spacing regulator 90 of the bill, check or other outer sheet 47 may be set for double or triple spacing, while the line-space regulator 99 for the record or other inner sheet 37 may be set for single spacing, for compactness of the record. To operate the ma-

chine for "condensed billing" or any condensed record work, the record sheet 37 is first introduced and positioned by means of the collating pins 46; and this sheet may be faced with a carbon, which, for this illustration, may be understood as 36; although, if desired, 36 may be a transpicuous sheet, and a double or two-faced carbon may be inserted between 36 and 37 for rendering all items written upon 36 visible to the operator whether written directly by the ribbon 23 or not. An invoice is then introduced into the chute 49, 50, in the manner already described, and carried down and up around both platens, and positioned by means of the registering pins 46. The types may be operated to write the address upon the invoice, and the duplicate type impressions may appear upon the record sheets 36, 37, but narrowly line-spaced. The items of the invoice may then be written until it is completed; and then the invoice may be withdrawn, and a fresh one inserted and registered or collated ready to be written upon, the record set 36, 37 remaining stationary at this time.

In order to remove the invoice, the roll 53 is swung up to release the same.

The platen 25 may be automatically line-spaced when thrown away from printing position, to give the record sheet thereon a blank line-space between successive groups of items. This may be done by a pawl 102, pivoted at 103 on the right-hand plate 28, and having a spring 103^a, and shown in an ineffective position in Fig. 4. This pawl may be rendered effective by moving it to the dot-and-dash line position indicated in Fig. 4, by pushing rearwardly on a finger-piece 104 on a lever 104^a, the movement of which is limited by a stop-pin 105, to permit spring 103^a to force the pawl 102 into the path of the teeth of the ratchet wheel 100, so that the latter is engaged by the pawl 102 to line-space the platen 25 automatically during the upward movement of the latter. To retain the pawl-acting lever 104^a in either effective or ineffective position, a suitable detent 105^a may be fixed on the lever to engage holes in the frame. The pawl may be silenced when writing invoices and statements in the manner hereinbefore described, as it is chiefly valuable in condensed billing or similar work where the items of successive invoices or the like are accumulated upon a single record sheet. The lever 104^a and the pawl may be concentrically pivoted, and the lever may have a pin 105^b to engage a toe 105^c on the pawl, for controlling the latter.

In some cases it is desirable to preserve a condensed general record of the entries made upon the successive statements referred to in the early part of the foregoing description, and for such purpose there may be used a 130

record sheet 106, Figs. 8 and 6, (preferably with an overlying carbon 107). This sheet with its carbon may be introduced in rear of a fixed member or cross-bar 108, Fig. 8, fixed at its ends upon the side plates 29 of the swing-up frame. The record sheet 106, which is to remain in the machine and preserve a carbon copy of all the entries made upon the successive inner sets 36, 37, may be wider than any of the other sheets in the machine; and by means of its overlapping margins it may be clipped against the cross-bar or support 108, by using yielding clips 109, one at each side of the machine. The clips 15 may be fixed upon the ends of the rock shaft 35, to be brought automatically into use to clip the sheet when the feed roll 39 is withdrawn, Fig. 8, and to release the sheet when 39 is restored to working position, Fig. 9. It 20 will be seen that devices for carrying this condensed record sheet 106 are mounted upon the swing-up frame, so that said sheet is carried out of the way when the platen 26 is brought into use. Hence, only abridged 25 records are accumulated upon 106. A tablet 110 may also be provided upon the swing-up frame, to support the sheets 106, 107 emerging at the delivery side of the machine, below the collating-table 45 and above the 30 introductory chutes.

In using the condensed record sheet 106 for accumulating entries of totals appearing upon different customers' statements, the preferred method is, as follows: At the 35 first insertion of the statement, the name is written upon the invoice, statement, ledger and condensed record sheets all at the same time, together with the date. Then the platen 25 is moved up, and the items are 40 written upon only the invoice sheet, by means of the lower platen 26. Then the platen 25 may be moved down again, and the total written upon the invoice, the statement, the ledger sheet, and the condensed 45 record sheet. This operation may be repeated for each succeeding statement. Successive statements are of course made out to different customers. Thus, there is kept on the condensed record sheet a daily record 50 of the names and entries of all the invoices for all the customers. On the following day, using fresh invoice sheets, it becomes necessary to introduce again the same statement and ledger sheet that were used on the 55 first day. It is also necessary to write the name and address upon the fresh invoices, and it is desirable that such names should be recorded also upon the condensed record sheet 106, although it is not desired to have 60 the name repeated upon the statement or ledger sheet. Therefore, on the second and following days, when an invoice is inserted, the name may be typed thereon before the statement and ledger sheets 36, 37 are inserted in the machine; the platen 25 at the 65

typewriting operation being in its depressed position, so that such name is also written upon the condensed record sheet 106. Then the invoice is inserted, and the date is written to appear upon all the sheets. Then 70 the platen 25 is swung up out of printing position, and the items are written upon the invoice sheet 47 by the use of the lower platen 26; whereupon the platen 25 is swung down again, and the total is printed upon all 75 the sheets. The condensed record sheet 106 may be in the form of a web if desired.

Variations may be resorted to within the scope of our invention, and portions of the improvements may be used without others. 80

Having described our invention, we claim:

1. The combination with a frame, of a platen revoluble for line-spacing and movable relatively to said frame to and away from printing position, a second platen connected to the first, so that either platen moves to printing position as the other moves away therefrom, the second platen mounted below the first, means for guiding and feeding work-sheets around the first platen, and means for guiding work-sheets to coöperate with either of said platens, the last-mentioned means including an introductory guide fixed upon said frame and extending from the rear downwardly and forwardly and under the second platen and up forwardly thereof, and also comprising a feeding couple upon said frame at the delivery side of the machine. 90

2. In a front-strike typewriting machine, 100 the combination with a platen frame, of a platen supported thereon and revoluble for line-spacing and movable to and away from the printing point, sheet-guiding means extending from the introductory side of the machine forwardly around the underside of said platen and up in front thereof to confine the portion of the sheet passing around the platen below the printing point, a second platen also supported upon said platen 105 frame below said confining means, and means also supported upon said platen frame for guiding and feeding another sheet forwardly and under the second platen and up in front of both platens to coöperate 110 with either thereof, whereby the platens may be compactly arranged in proximity to each other without rendering the first-mentioned sheets inaccessible for the usual preliminary manipulation at the delivery side of the 115 typewriting platen. 120

3. In a front-strike typewriting machine, the combination with a platen frame, of a platen supported thereon and revoluble for line-spacing and movable to and away from printing position, means for guiding and feeding sheets forwardly around the underside of said platen, said feeding means including a roll to run upon the underside of 125 the platen, a second platen mounted below 130

- the first and in front of said roll, and means for guiding and supporting a work-sheet in position to coöperate with either platen, said guiding and supporting means including a bent guide extending from the rear of the machine forwardly below said feed roll and said second platen and up in front of the latter, and also including feeding means arranged above said revolute platen.
10. 4: In a front-strike typewriting machine, the combination with a platen frame, of a platen supported thereon and revolute for line-spacing and movable to and away from printing position, means for guiding and 15 feeding sheets forwardly around the under side of said platen; said feeding means including a roll to run upon the underside of the platen, a second platen mounted below the first and in front of said roll, and means for guiding and supporting a work-sheet 20 in position to coöperate with either platen, said guiding and supporting means including a chute extending from the rear of the machine forwardly and downwardly and 25 bending forwardly and upwardly toward the front of the revolute platen, said feed roll and said second platen confined within the bend of said chute.
5. The combination with a frame, of a 30 platen supported thereon and revolute for line-spacing and having sheet-feeding means, and movable to and away from the printing point, sheet-guiding means extending from the rear beneath said platen to the 35 front thereof and movable bodily with said platen as the latter moves to and from the printing point, a second platen below said sheet-guiding means and connected to said revolute platen to move to the printing 40 point as the revolute platen moves away therefrom, and means for supporting a work-sheet in position to coöperate with either platen.
6. The combination with a frame, of a 45 platen supported thereon and revolute for line-spacing and having sheet-feeding means, and movable to and away from the printing point, sheet-guiding means extending from the rear beneath said platen to the 50 front thereof and movable bodily with said platen as the latter moves to and from the printing point, a second platen below said sheet-guiding means and connected to said revolute platen to move to the printing 55 point as the revolute platen moves away therefrom, and means for supporting a work-sheet in position to coöperate with either platen, said supporting means including a sheet guide extending from behind the 60 second platen forwardly under and up forwardly of the same, and also including feeding means arranged above said revolute platen.
7. The combination with a frame and a 65 plurality of platens supported thereon for up and down movement into and out of printing position, of a relatively fixed chute extending downwardly and forwardly under said platens and bending upwardly to guide the work-sheet toward the printing point 70 for coöperation with either platen.
8. The combination with a frame and a plurality of platens supported thereon for up-and-down movement into and out of printing position, of a relatively fixed chute 75 extending downwardly and forwardly under said platens and bending upwardly to guide the work-sheet toward the printing point for coöperation with either platen, and a feeding couple for said sheet above 80 said platens.
9. The combination with a frame and a plurality of platens supported thereon for up and down movement into and out of printing position, of a relatively fixed chute 85 extending downwardly and forwardly under said platens and bending upwardly to guide the work-sheet toward the printing point for coöperation with either platen, a feeding couple for said sheet above said platens, 90 one of said platens being mounted above the other and being of relatively extensive cross-section and revolute for line-spacing, and a paper-guiding apron movable with said revolute platen for coöperation there- 95 with and nested within the bend of said chute.
10. The combination with a frame and a plurality of platens supported thereon for up-and-down movement into and out of printing position, of a relatively fixed chute 100 extending downwardly and forwardly under said platens and bending upwardly to guide the work-sheet toward the printing point for coöperation with either platen, a feed- 105 ing couple for said sheet above said platens, one of said platens being mounted above the other and being of relatively extensive cross-section and revolute for line-spacing, a paper-guiding apron movable with said 110 revolute platen for coöperation therewith and nested within the bend of said chute, and a fender being provided to close the space behind said apron, to guard against the introduction of sheets between the chute 115 and the apron.
11. In a front-strike typewriting machine, the combination with a platen frame, of a plurality of platens supported thereon one above another, means for feeding inner 120 work-sheets around one of said platens, said platens shiftable up and down to move them to and from printing positions, a chute extending from the rear below said platens and bending upwardly at its forward portion 125 to guide outer sheets up in front of said platens to coöperate with either thereof, and a feeding couple above said platens for said outer sheets.
12. The combination with a frame, of an 130

- up-and-down movable frame mounted thereon, a platen revoluble for line-spacing and journaled upon said movable frame, a paper guide upon said movable frame and 5 extending downwardly in rear of said platen and forwardly under the same to the front thereof, a relatively fixed platen upon said movable frame below said paper guide, a chute upon said platen frame and extending downwardly in rear of said platens and forwardly under said fixed platen and upwardly toward the printing point, and a feeding couple upon said first frame above the revoluble platen for feeding the sheet 10 which is guided through said chute.
13. The combination with a frame, of a feeding couple at the upper forward portion thereof, a chute at the lower and rear portions thereof, a frame mounted for movement upon said platen frame, upper and lower platens carried upon said movable frame to move them in alternation to and away from printing position, and a feed roll to run upon the underside of the upper 20 platen, said chute having at its lower forward portion a bend occupied by said lower platen and said roll.
14. The combination with a frame, of a feeding couple at the upper forward portion thereof, a chute at the lower and rear portions thereof, a frame mounted for movement upon said platen frame, upper and lower platens carried upon said movable frame to move them in alternation to and 30 away from printing position, a feed roll to run upon the under side of the upper platen, said chute having at its lower forward portion a bend occupied by said lower platen and said roll, and a paper apron also within said 35 bend and extending downwardly and rearwardly to the upper platen and curving forwardly under the same to the front thereof.
15. The combination with a frame, of a feeding couple at the upper forward portion thereof, a chute at the lower and rear portions thereof, a frame mounted for movement upon said platen frame, upper and lower platens carried upon said movable frame to move them in alternation to and 40 away from printing position, a feed roll to run upon the under side of the upper platen, said chute having at its lower forward portion a bend occupied by said lower platen and said roll, and a paper apron also within 45 said bend and extending downwardly and rearwardly to the upper platen and curving forwardly under the same to the front thereof, said chute comprising both a rear plate and a forward plate, the forward plate at 50 its upper end flaring forwardly to facilitate introducing sheets, and also to close the space between said forward plate and said apron and thereby guard against misplacing the work-sheets.
16. The combination with a platen frame 55 and a plurality of platens mounted thereon one above another and movable to and away from printing position, whereby either platen may be used, of a chute extending forwardly under said platens and bending to direct sheets up in front of said platens, and releasable feed rolls above said platens for feeding sheets that pass through said chute.
17. The combination with a platen frame and a plurality of platens mounted thereon one above another and movable to and away from printing position, whereby either platen may be used, of a chute extending forwardly under said platens and bending to direct sheets up in front of said platens, 70 releasable feed rolls above said platens for feeding sheets that pass through said chute, and means being provided for mechanically holding said feed rolls released.
18. The combination of a revoluble platen, sheet-feeding means therefor, a relatively fixed platen, means for moving the platens into and out of printing positions, and means to feed sheets to position to coöperate with either platen, comprising a feeding couple 80 arranged above both platens and a sheet guide arranged under said platens, said sheet guide and feeding couple being so placed relatively to said platens that the sheets carried thereby are bulged forward at the printing point by either platen, whereby the sheet is kept taut upon the platen.
19. In a front-strike writing machine, the combination with a platen frame, of two platens supported thereon, one of said 100 platens of relatively small and the other of relatively extensive cross-section, the large platen revoluble for line-spacing, and said platens movable to bring either to the printing point, a feed roll running upon the under side of the large platen, said large platen, and roll forming a couple to which the work-sheets are presented for introduction into the machine, means to coöperate with said roll to confine work-sheets against the under side of said large platen and conduct them forwardly around to the front thereof, and means for supporting and guiding an outer work-sheet in position to coöperate with either platen, said supporting and guiding 110 means including means to guide said outer work-sheet downwardly at the rear and forwardly under the small platen and upwardly in front of both platens, whereby the outer work-sheet forms a bend or loop, said 115 small platen and said roll lying within said bend or loop in said outer work-sheet.
20. The combination with a platen frame, of a platen mounted thereon and revoluble for line-spacing, a device above said platen 125 on which to register the sheets preparatory to a typing operation, and a second platen below the first, said platens being movable to and away from the printing point in alternation to bring either platen into use.

21. The combination with a platen frame, of a platen mounted thereon and revoluble for line-spacing, from the printing point, a device above said platen on which to register the sheets preparatory to a typing operation, a second platen below the first, said platens being movable to and away from the printing point in alternation to bring either platen into use, and means for supporting and guiding a sheet for coöperation with either platen, said supporting and guiding means including parts in proximity to said registering device, for controlling a sheet registered thereon. 70
22. The combination with a frame, of a sheet-registering tablet thereon, a plurality of platens supported one above another upon said frame and movable into and out of printing positions, means for feeding an inner sheet around one of said platens, and means for supporting and guiding an outer sheet to position for coöperation with either platen, said registering tablet in position to register both the inner and outer sheets. 80
23. The combination of a sheet registering or collating-table, a revoluble line-spacing platen below said table, a second platen below the revoluble platen, said platens mounted for up-and-down movements to and from printing positions, means coöoperating with the upper platen to feed sheets around the same, and means for supporting and guiding an outer sheet to position for coöperation with either platen, including both sheet-guiding means below the lower platen, and sheet-controlling means above the upper platen in proximity to said table, whereby both inner and outer sheets may be registered or collated upon the table. 90
24. The combination with a platen frame, of a registering or collating table thereon, a platen revoluble for line-spacing and underlying said table, a releasable feed roll to run upon the under side of said platen in position to clamp an inner sheet while registered upon said table, a second platen below said revoluble platen, means for shifting said platens up and down to and away from printing positions, and means for supporting and feeding an outer sheet to coöperate with either platen, including a releasable sheet-clamping means in position to clamp the outer sheet while it is registered upon said table. 100
25. The combination with a platen frame, of a registering or collating table thereon, a platen revoluble for line-spacing and underlying said table, a releasable feed roll to run upon the under side of said platen in position to clamp an inner sheet while registered upon said table, a second platen below said revoluble platen, means for shifting said platens up and down to and away from printing positions, a chute for guiding an outer sheet, said chute extending from the rear of said platens forwardly under said roll and said second platen and upwardly toward the printing point, and a feeding couple for the outer sheet above the printing point and in proximity to the front of the collating table, to clamp an outer sheet that is registered thereon. 110
26. The combination of a main frame, a sheet-collating or registering table fixed thereon, two platens one above another supported upon said frame for movement into and out of printing positions below said collating table, one of said platens being revoluble for line-spacing, and means upon said frame for guiding and feeding sheets to coöperate with either of said platens, including a releasable feeding couple in proximity to the registering table to clamp the sheets while they remain registered, said revoluble platen having releasable means to clamp the sheets thereon while they also remain registered on said table. 120
27. The combination with a platen frame and a plurality of platens mounted thereon one above another and movable to and away from printing position, whereby either platen may be used, of a chute extending forwardly under said platens and bending to direct sheets up in front of said platens, releasable feed rolls forming a couple above said platens for feeding sheets that pass through said chute, one of said platens being revoluble, releasable means to feed sheets around said revoluble platen, and a sheet-registering board in position to be employed for registering a sheet extending from said board around said revoluble platen and between the platen and the feed roll, and also a sheet extending through said feeding couple from said chute. 130
28. The combination of a collating table, a platen revoluble for line-feeding and disposed beneath said table, means at said platen to receive an inner sheet as it is introduced into the machine, and guide it forwardly under the platen, releasable feeding means to press the inner sheet against the platen while it is registered upon said collating table, a second platen below the first and movable into and out of printing position, a chute extending downwardly at the rear of the machine and bending forwardly under said second platen, and a line-feeding couple above the platens to coöperate with the chute to guide and feed an outer sheet, said line-feeding couple in position to clamp the outer sheet while it is collated upon the collating table. 140
29. The combination with a collating table upon which an inner sheet and an outer sheet may be collated in different relationships, of a line-feeding platen for the inner sheet, a releasable sheet-feeding device to coöperate with the platen, said platen movable into and out of printing position, a second platen 150

also movable into and out of printing position, said platens mounted one above another, and means for guiding and feeding an outer sheet for cooperation with either 5 platen, including a releasable sheet-feeding device, said sheet-feeding devices being in position to clamp the sheets while they remain collated upon said table.

30. The combination with a collating table 10 upon which inner sheets and outer sheets may be collated in different relationships, of releasable means for feeding the outer sheet, said releasable means being in position to clamp the sheet while it is collated upon 15 said table, means for feeding the inner sheet, said inner-sheet-feeding means being positioned to clamp the inner sheet while it is registered upon said table, and shiftable means for enabling typewriting to be done 20 upon either the outer sheet alone or upon both the outer and inner sheets, at will.

31. The combination with a collating table upon which inner sheets and outer sheets may be collated in different relationships, 25 of releasable means for feeding the outer sheet, said releasable means being in position to clamp the sheet while it is collated upon said table, means for feeding the inner sheet, said inner-sheet-feeding means being 30 positioned to clamp the inner sheet while it is registered upon said table, shiftable means for enabling typewriting to be done upon either the outer sheet alone or upon both the outer and inner sheets, at will, a 35 single manually-operable member, means controlled thereby for operating the outer-sheet-feeding means, and separate means controlled by said manually-operable member for operating the inner-sheet-feeding 40 means.

32. The combination of a collating table, a platen revoluble for line-feeding and disposed beneath said table, means to receive an inner sheet as it is introduced into the machine and guide it forwardly under the 45 platen, releasable feeding means to press the sheet against the platen while it is registered upon said collating table, a second platen below the first and movable into and out of printing position; a chute extending downwardly at the rear of the machine and bending forwardly under said second platen, a line-feeding couple above the platens to 50 operate with the chute to guide and feed an outer sheet, said line-feeding couple in position to clamp the outer sheet while it is registered upon the collating table, and means cooperating with said revoluble platen and said feeding couple to line-space 55 the outer and inner sheets simultaneously.

33. The combination of a collating table, a platen revoluble for line-feeding and disposed beneath said table, means to receive an inner sheet as it is introduced into the 60 machine and guide it forwardly under the

platens, releasable feeding means to press the sheet against the platen while it is registered upon said collating table, a second platen below the first and movable into and out of printing position, a chute extending 70 downwardly at the rear of the machine and bending forwardly under said second platen, a line-feeding couple above the platens to cooperate with the chute to guide and feed an outer sheet, said line-feeding couple in position to clamp the outer sheet while it is registered upon the collating table, means cooperating with said revoluble platen and said feeding couple to line-space 75 the outer and inner sheets simultaneously, 80 said revoluble platen being disconnected from the line-spacing means when out of printing position, and provision being made for line-feeding the outer sheet while the revoluble platen is out of printing position. 85

34. The combination with a platen frame, of upper and lower platens mounted thereon for movement into and out of printing positions, paper-feeding devices for one of said platens to control an inner sheet, line-spacing mechanism to cooperate with said paper-feeding devices, means for guiding and feeding an outer sheet to cooperate with either of said platens, and line-spacing 90 mechanism to cooperate with said feeding means for the outer sheet.

35. The combination with a platen frame, of upper and lower platens mounted thereon for movement into and out of printing positions, paper-feeding devices for one of said platens to control an inner sheet, line-spacing mechanism to cooperate with said paper-feeding devices, means for guiding and feeding an outer sheet to cooperate with either of said platens, and line-spacing 100 mechanism to cooperate with said feeding means for the outer sheet, said line-spacing mechanism connected for simultaneous operation.

36. The combination with a platen frame, 110 of upper and lower platens mounted thereon for movement into and out of printing positions, paper-feeding devices for one of said platens to control an inner sheet, line-spacing mechanism to cooperate with said paper-feeding devices, means for guiding and feeding an outer sheet to cooperate with either of said platens, and line-spacing mechanism 115 to cooperate with said feeding means for the outer sheet, said line-spacing mechanism connected for simultaneous operation, and the line-spacing mechanism for the inner sheet having provision whereby it may be silenced at will, so that the outer sheet 120 may be line-spaced while the inner sheet 125 remains stationary.

37. The combination with a platen frame, of upper and lower platens mounted thereon for movement into and out of printing positions, paper-feeding devices for one of said 130

- platens to control an inner sheet, line-spacing mechanism to coöperate with said paper-feeding devices, means for guiding and feeding an outer sheet to coöperate with either of said platens, line-spacing mechanism to coöperate with said feeding means for the outer sheet, said line-spacing mechanisms connected for simultaneous operation, the platen for the inner sheet being revoluble for line-spacing, and means being provided for disconnecting the revoluble platen from the control of the line-spacing mechanism at the movement of said platen away from printing position.
15. 38. The combination with a platen revoluble for line-spacing, of a second platen, said platens arranged one above the other and supported for movement into and out of printing positions, means coöoperating with said revoluble platen to feed an inner sheet, means for guiding and feeding an outer sheet for coöperation with either of said platens, said guiding and feeding means including a feed-roll; a line-spacing handle, and driving connections from said line-spacing handle to said revoluble platen and to said feed-roll, to line-space both inner and outer sheets.
39. The combination with a platen revoluble for line-spacing, of a second platen, said platens arranged one above the other and supported for movement into and out of printing positions, means coöoperating with said revoluble platen to feed an inner sheet, means for guiding and feeding an outer sheet for coöperation with either of said platens, said guiding and feeding means including a feed-roll; a line-spacing handle, and driving connections from said line-spacing handle to said platen and to said feed-roll, to line-space both inner and outer sheets, means being provided for effecting a disconnection between the line-space handle and the revoluble platen, whereby the outer sheet may be line-spaced by said handle while the inner sheet remains stationary.
40. The combination with a platen revoluble for line-spacing, of a second platen, said platens arranged one above the other and supported for movement into and out of printing positions, means coöoperating with said revoluble platen to feed an inner sheet, means for guiding and feeding an outer sheet for coöperation with either of said platens, said guiding and feeding means including a feed-roll; a line-spacing handle, and driving connections from said line-spacing handle to said platen and to said feed-roll, to line-space both inner and outer sheets, means being provided for effecting a disconnection between the line-space handle and the revoluble platen and simultaneously moving said revoluble platen away from printing position, so that the inner sheet will neither be written upon nor line-spaced during the operations of writing upon and line-spacing the outer sheet.
41. The combination with a platen frame, of a platen revoluble for line feeding an inner sheet, a second platen, said platens mounted one above another and movable upon said frame into and out of printing positions, line-feeding means including a roll for an outer sheet to coöperate with either of said platens, a line-spacing handle, and line-spacing mechanism ramifying from said handle to said revoluble platen and said line-feeding roll.
42. The combination with a platen frame, of a platen revoluble for line feeding an inner sheet, a second platen, said platens mounted one above another and movable upon said frame into and out of printing positions, line-feeding means including a roll for an outer sheet to coöperate with either of said platens, a line-spacing handle, and line-spacing mechanism ramifying from said handle to said revoluble platen and said line-feeding roll for line-spacing inner and outer sheets simultaneously, provision being made for line-spacing the outer sheet independently of the inner sheet, so that the latter may be stationary while the outer sheet is being line-spaced.
43. The combination with a platen frame, of a platen revoluble for line feeding an inner sheet, a second platen, said platens mounted one above another and movable upon said frame into and out of printing positions, line-feeding means including a roll for an outer sheet to coöperate with either of said platens, a line-spacing handle, line-spacing mechanism ramifying from said handle to said revoluble platen and said line-feeding roll, and means dependent upon the movement of said revoluble platen out of printing position for disconnecting it from said handle, to permit the writing and line-spacing of the outer sheet while the inner sheet is neither typewritten nor line-spaced.
44. In a front-strike typewriting machine, the combination with a plurality of platens mounted one above another and movable into and out of printing position, so that typewriting may be done upon either platen, of means for line-spacing a sheet, means for supporting an inner sheet upon one of said platens and effecting line-space movements of said inner sheet, and means for supporting and line-spacing an outer sheet to coöperate with either of said platens, including means for line-spacing said outer sheet either simultaneously with or independently of the inner sheet.
45. In a front-strike typewriting machine, the combination with a plurality of platens mounted one above another and movable into and out of printing position, so that type-

- writing may be done upon either platen, of a line-spacing mechanism including both means for line-spacing an inner sheet which coöperates with one platen and also means for line-spacing an outer sheet to coöperate with either platen, said line-spacing mechanism including a reciprocatory operating means manipulable by the operator at a single stroke for both sheets.
46. In a front-strike typewriting machine, the combination with a plurality of platens mounted one above another and movable into and out of printing position, so that typewriting may be done upon either platen, of a line-spacing mechanism including both means for line-spacing an inner sheet which coöperates with one platen and also means for line-spacing an outer sheet to coöperate with either platen, said line-spacing mechanism including a reciprocatory operating means manipulable by the operator at a single stroke for both sheets, means being provided for effecting a disconnection between the line-feeding means of the inner sheet and said reciprocatory operating means.
47. The combination with a platen revolvable for line-spacing, of means to coöperate therewith to feed an inner sheet, a second platen, said platens being mounted for movement into and out of printing positions to bring either platen into use at will, means including a feed roll for feeding and guiding an outer sheet to coöperate with either of said platens, a manipulable line-spacing handle or member, and driving connections ramifying from said handle to said platens and said feed roll.
48. The combination with a platen revolvable for line-spacing, of means to coöperate therewith to feed an inner sheet, a second platen, said platens being mounted for movement into and out of printing positions to bring either platen into use, at will, means including a feed roll for feeding and guiding an outer sheet to coöperate with either of said platens, a manipulable line-spacing handle or member, and driving connections ramifying from said handle to said platens and said feed roll, and including a gear couple in the connection which goes to said revolvable platen, the members of which gear couple become meshed upon a movement of the revolvable platen to printing position and unmeshed upon the return movement.
49. The combination with a platen revolvable for line-spacing, of means to coöperate therewith to feed an inner sheet, a second platen, said platens being mounted for movement into and out of printing positions to bring either platen into use, at will, means including a feed roll for feeding and guiding an outer sheet to coöperate with either of said platens, a manipulable line-spacing handle or member, a pawl-and-ratchet mechanism driven by said handle and connected to said revolvable platen, and a second pawl-and-ratchet mechanism driven by said handle and connected to said feed roll.
50. The combination with a platen revolvable for line-spacing, of means to coöperate therewith to feed an inner sheet, a second platen, said platens being mounted for movement into and out of printing positions to bring either platen into use, at will, means including a feed roll for feeding and guiding an outer sheet to coöperate with either of said platens, a manipulable line-spacing handle or member, and driving connections ramifying from said handle to said platens and said feed roll, means being provided to disable the connection between the manipulable handle and the revolvable platen while the connection from said handle to said feed roll remains effective.
51. The combination with means including alternate platens movable up and down to bring them into and out of printing positions, for guiding inner and outer sheets and typewriting upon either the outer sheet alone or upon both outer and inner sheets simultaneously, of a line-spacing mechanism including means reciprocable manually for line-spacing both sheets.
52. The combination with means including alternate platens movable up and down to bring them into and out of printing positions, for guiding inner and outer sheets and typewriting upon either the outer sheet alone or upon both outer and inner sheets simultaneously, of a line-spacing mechanism including means reciprocable manually for line-spacing both sheets, and also including a provision for silencing the line-spacing movement of the inner sheet while the line-spacing movement of the outer sheet continues, at will.
53. The combination of a plurality of platens mounted one above another and supported for movement into and out of printing positions, sheet-guiding means for one of said platens to control an inner sheet, means for guiding and feeding an outer sheet for coöperation with either of said platens, including a feeding couple at the delivery side of the machine, a line-space handle, a pawl-and-ratchet wheel mechanism operated by said line-space handle, and driving connections from said ratchet-wheel to said feeding couple.
54. The combination with a platen frame and two platens mounted for movement thereon into and out of printing position, one platen above the other, of means including a feeding couple at the delivery side of the machine, and also including a reciprocating line-spacing mechanism connected to said feeding couple, for line-spacing and guiding sheets to coöperate with whichever platen may be in printing position.
55. The combination with a platen frame

- and two platens mounted for movement thereon into and out of printing position, one platen above the other, of means, including a feeding couple at the delivery side 5 of the machine, for feeding and guiding sheets to coöperate with either platen.
56. The combination with a platen frame and two platens mounted for movement thereon into and out of printing position, 10 one platen above the other, of means, including a feeding couple at the delivery side of the machine, for feeding and guiding sheets to coöperate with either platen, a line-space lever mounted upon said platen frame, a ratchet wheel, a pawl driven by said lever for operating said ratchet wheel, a gear operated by said ratchet wheel, and a pinion connected to said gear and operating a member of said feeding couple.
57. The combination with a platen frame and two platens mounted for movement thereon into and out of printing position, one platen above the other, of means, including a feeding couple at the delivery side 15 of the machine, for feeding and guiding sheets to coöperate with either platen, a line-space lever mounted upon said platen frame, a ratchet wheel, a pawl driven by said lever for operating said ratchet wheel, a gear operated by said ratchet wheel, and a pinion connected to said gear and operating a member of said feeding couple, one of said platens being revoluble for line-spacing and having a driving connection 20 with said line-space lever.
58. The combination with a platen frame and two platens mounted for movement thereon into and out of printing position, one platen above the other, of means, including a feeding couple at the delivery side 25 of the machine, for feeding and guiding sheets to coöperate with either platen, a line-space lever mounted upon said platen frame, a ratchet wheel, a pawl driven by said lever for operating said ratchet wheel, a gear operated by said ratchet wheel, and a pinion connected to said gear and operating a member of said feeding couple, one of said platens being revoluble for line-spacing and having a driving connection 30 with said line-space lever.
59. The combination with a platen frame and two platens mounted for movement thereon into and out of printing position, one platen above the other, of means, including a feeding couple at the delivery side 35 of the machine, for feeding and guiding sheets to coöperate with either platen, a line-space lever mounted upon said platen frame, a ratchet wheel, a pawl driven by said lever for operating said ratchet wheel, a gear operated by said ratchet wheel, and a pinion connected to said gear and operating a member of said feeding couple, one of said platens being revoluble for line-spacing and having a driving connection 40 with said line-space lever, said driving connection including a pinion operated by said line-space lever, and a platen gear also meshing with said pinion.
60. The combination with a platen frame and two platens mounted for movement thereon into and out of printing position, one platen above the other, of means, including a feeding couple at the delivery side 45 of the machine, for feeding and guiding sheets to coöperate with either platen, a line-space lever mounted upon said platen frame, a ratchet wheel, a pawl driven by said lever for operating said ratchet wheel, a gear operated by said ratchet wheel, and a pinion connected to said gear and operating a member of said feeding couple, one of said platens being revoluble for line-spacing and having a driving connection 50 with said line-space lever, said driving connection including a pinion operated by said line-space lever, and a platen gear also meshing with said pinion.
61. The combination with two platens mounted one above another for up-and-down movement into and out of printing position, and means for supporting and feeding a work-sheet to coöperate with whichever platen is in printing position, one of said platens being revoluble, of a line-space handle, a pawl-and-ratchet wheel driven thereby, a pinion driven by said ratchet wheel, and a gear on said revoluble platen meshing with said pinion and disengageable therefrom when the revoluble platen moves out of printing position.
62. The combination with two platens one above the other and movable up and down into and out of printing position, of means for line-spacing at unlike speeds by a single operation both a sheet which coöperates with 105 one of said platens and a sheet which coöperates with whichever platen is in printing position.
63. The combination of a line-spacing handle, two pawls pivoted thereto, two concentric line-space wheels engageable by said pawls, a shaft upon which one of said line-space wheels is mounted, a gear upon said shaft spaced from its line-space wheel, a sheet-feeding couple driven by said gear, two 110 platens one above another and movable up and down into and out of printing position, said feeding couple controlling a sheet to coöperate with whichever platen is in printing position, a hollow shaft upon said shaft 115

and arranged between said line-space wheel and said gear, the second line-space wheel being mounted upon said hollow shaft, a gear upon said hollow shaft, and an idle pinion meshing with the last-mentioned gear, one of said platens being revoluble and having a gear to mesh with said idle pinion.

64. The combination of a line-spacing handle, two pawls pivoted thereto, two concentric line-space wheels engageable by said pawls, a shaft upon which one of said line-space wheels is mounted, a gear upon said shaft spaced from its line-space wheel, a sheet-feeding couple driven by said gear, two platens one above another and movable up and down into and out of printing position, said feeding couple controlling a sheet to coöperate with whichever platen is in printing position, a hollow shaft upon said shaft and arranged between said line-space wheel and said gear, the second line-space wheel being mounted upon said hollow shaft a gear upon said hollow shaft, and an idle pinion meshing with the last-mentioned gear, one of said platens being revoluble and having a gear to mesh with said idle pinion, and to move away therefrom as the revoluble platen moves out of printing position.

65. The combination of a line-spacing handle, two pawls pivoted thereto, two concentric line-space wheels engageable by said pawls, a shaft upon which one of said line-space wheels is mounted, a gear upon said shaft spaced from its line-space wheel, a sheet-feeding couple driven by said gear, two platens one above another and movable up and down into and out of printing position, said feeding couple controlling a sheet to coöperate with whichever platen is in printing position, a hollow shaft upon said shaft and arranged between said line-space wheel and said gear, the second line-space wheel being mounted upon said hollow shaft, a gear upon said hollow shaft, an idle pinion meshing with the last-mentioned gear, one of said platens being revoluble and having a gear to mesh with said idle pinion, and means to regulate the line-spacing movements of either ratchet wheel, regardless of the other.

66. The combination of two platens, one above another and mounted to move up and down to bring them into and out of printing positions, one of said platens being revoluble, regulatable line-spacing devices for said revoluble platen, a feeding couple at the delivery side of the machine for feeding a sheet in coöperation with whichever platen may be in printing position, and regulatable line-spacing means for said feeding couple.

67. The combination of two platens, one above another and mounted to move up and down into and out of printing positions, one of said platens being revoluble for line-

spacing, and a feeding couple for feeding sheets to coöperate with whichever platen may be in printing position, provision being made for line-spacing said revoluble platen and said feeding couple, and means being also provided for effecting relative regulation of the line-spacing movements of said revoluble platen and said feeding couple.

68. The combination of two platens, one above another and mounted to move up and down into and out of printing positions, one of said platens being revoluble for line-spacing, and a feeding couple for feeding sheets to coöperate with whichever platen may be in printing position, provision being made for line-spacing said revoluble platen and said feeding couple, and means being also provided for effecting regulation of the line-spacing of said feeding couple while the line-spacing of said revoluble platen remains unchanged.

69. The combination of two platens, one above another and mounted to move up and down into and out of printing positions, one of said platens being revoluble for line-spacing, and a feeding couple for feeding sheets to coöperate with whichever platen may be in printing position, provision being made for line-spacing said revoluble platen and said feeding couple, and means being also provided for effecting regulation of the line-spacing of said revoluble platen while the line-spacing of said feeding couple remains unchanged.

70. The combination of two platens, one above another and mounted to move up and down into and out of printing positions, one of said platens being revoluble for line-spacing, and a feeding couple for feeding sheets to coöperate with whichever platen may be in printing position, provision being made for line-spacing said revoluble platen and said feeding couple, and means being also provided for effecting regulation of the line-spacing of either said revoluble platen or said feeding couple, while the regulation of the other remains unchanged.

71. The combination with two platens mounted for movement into and out of printing position, one platen above the other, of means, including a feeding couple, for feeding and guiding sheets to coöperate with whichever platen may be in printing position, a line-space lever, a pawl and ratchet-wheel driven by said lever, a line-space regulator to vary the extent to which the ratchet-wheel is driven by the pawl, and a train of gearing from said ratchet-wheel to a member of said feeding couple.

72. In a front-strike typewriting machine, the combination with a plurality of superposed platens movable bodily into and out of printing positions, of means for feeding a sheet over one platen, means for

feeding a separate sheet over whichever platen is in printing position, devices for releasing said feeding means, and means for retaping a record sheet stationary in the machine while said devices are effective to permit movements of the aforesaid sheets relative to the feeding means.

73. The combination with a plurality of superposed platens movable bodily into and out of printing positions, of means for holding a condensed record sheet in position upon one of said platens while another sheet is being positioned relatively to such record sheet, and means for supporting and feeding a sheet to coöperate with whichever platen is in printing position.

74. In a front-strike typewriting machine, the combination of a platen revoluble for line-spacing, a relatively fixed platen beneath said platen, means for holding a record sheet in position upon said revoluble platen while another sheet is being positioned relatively to the same, and means for supporting and line-feeding an outer sheet to coöperate with whichever of said platens is in printing position.

75. The combination with a revoluble platen having a downwardly and forwardly inclined introductory paper shelf, of a supporting device arranged above said paper shelf, a feed roll to run upon said platen, pivoted arms carrying said feed roll, means extending from said arms to said supports to clip a condensed record sheet against the same when the feed roll is cast off, a second platen, said platens movable up and down to bring them into and out of printing positions together with said feed roll and paper clip, and means for guiding and feeding an outer sheet to coöperate with whichever platen is in printing position.

76. The combination with a revoluble platen having a downwardly and forwardly inclined introductory paper shelf, of a supporting device arranged above said paper shelf, a feed roll to run upon said platen, pivoted arms carrying said feed roll, means extending from said arms to said supports to clip a condensed record sheet against the same when the feed roll is cast off, a second platen, said platens movable up and down to bring them into and out of printing positions together with said feed roll and paper clip, means for guiding and feeding an outer sheet to coöperate with whichever platen is in printing position, a paper table for supporting the condensed record sheet, and a collating table above said paper table upon which to collate or register inner and outer sheets while said condensed record sheet remains held stationary by said clip.

77. The combination with separate platens for an inner sheet and an outer sheet, said platens movable into and out of printing

positions, of means for enabling said inner sheet to coöperate with only one of said platens, means to enable the outer sheet to coöperate with either platen, a collating or registering table upon which said inner and outer sheets may be registered in any desired relation, and means for maintaining a condensed record sheet upon the first platen while the other sheets are collated upon said table.

78. In a front-strike typewriting machine, the combination with means for feeding and holding an outer sheet, of means for supporting a condensed record sheet in position to receive carbon impressions of the matter written upon said outer sheet, and means for temporarily holding the record sheet to permit the introduction, after such writing, of a sheet between said outer sheet and said condensed record sheet.

79. In a front-strike typewriting machine, the combination with means for feeding and holding an outer sheet, of means for supporting a condensed record sheet in position to receive carbon impressions of the matter written upon said outer sheet, means for temporarily holding the record sheet to permit the introduction, after such writing, of a sheet between said outer sheet and said condensed record sheet, and means for shifting the supporting means to cause the outer sheet to be written upon either with or independently of said record and intervening sheet.

80. In a front-strike typewriting machine, the combination with means for feeding and holding an outer sheet, of means for supporting a condensed record sheet in position to receive carbon impressions of the matter written upon said outer sheet, means for temporarily holding the record sheet to permit the introduction, after such writing, of a sheet between said outer sheet and said condensed record sheet, means for shifting the supporting means to cause the outer sheet to be written upon either with or independently of said record and intervening sheet, and means for collating said outer and intervening sheets.

81. The combination of a frame, a platen revoluble for line-spacing, a second frame carrying said platen and movable upon the first frame to bring said platen into and out of printing position, means upon said second frame to move therewith for releasably clipping a condensed record sheet carried about said platen, a second platen also movable into and out of printing position, and means for guiding and feeding an outer sheet to coöperate with either of said platens.

82. The combination of a frame, a platen revoluble for line-spacing, a second frame carrying said platen and movable upon the first frame to bring said platen into and out of printing position, means upon said second

- frame to move therewith for releasably clipping a condensed record sheet carried about said platen, a second platen also movable into and out of printing position, means 5 for guiding and feeding an outer sheet to coöperate with either of said platens, and means for automatically effecting between entries a line-feeding movement of said condensed record sheet.
- 10 83. The combination of a frame, a platen revoluble for line-spacing, a second frame carrying said platen and movable upon the first frame to bring said platen into and out of printing position, means upon said 15 second frame to move therewith for releasably clipping a condensed record sheet carried about said platen, a second platen also movable into and out of printing position, means for guiding and feeding an outer sheet to coöperate with either of said platens, and means dependent upon the movement of 20 said revoluble platen between printing and non-printing positions for effecting automatic line-spacing of said platen.
- 25 84. The combination of a frame, a platen revoluble for line-spacing, a second frame carrying said platen and movable upon the first frame to bring said platen into and out of printing position, means upon said 30 second frame to move therewith for releasably clipping a condensed record sheet carried about said platen, a second platen also movable into and out of printing position, means for guiding and feeding an outer sheet to coöperate with either of said platens, 35 means dependent upon the movement of said revoluble platen between printing and non-printing positions for effecting automatic line-spacing of said platen, and means 40 for silencing said automatic line-spacing means, at will.
85. The combination of a frame, a platen revoluble for line-spacing, a second frame whereon said platen is mounted, a feed roll 45 mounted upon said second frame, said second frame being adjustable upon the first to carry said platen into and out of printing position, sheet-clipping means mounted upon said second frame and connected to 50 become effective when said feed roll is thrown off from said platen; a second platen also mounted for movement into and out of printing position, and means for guiding and feeding an outer sheet in position to co- 55 operate with whichever platen is in printing position.
86. The combination with a frame, of superposed platens movable bodily into and out of printing position, a second frame 60 upon which one of said platens is mounted for said movement, a device upon said second frame for holding a condensed record sheet stationary while other sheets are advanced or adjusted upon the platen, and means for feeding and guiding an outer 65 sheet in position to coöperate with either platen.
87. The combination with a frame, of superposed platens movable bodily into and out of printing position, a second frame 70 upon which one of said platens is mounted for said movement, a device upon said second frame for holding a condensed record sheet stationary while other sheets are advanced or adjusted upon the platen, means 75 for feeding and guiding an outer sheet in position to coöperate with either platen, and means upon the first frame for collating both the outer sheet and the intervening sheet.
88. The combination with a frame, of a second frame mounted for up-and-down movement thereon, a platen revoluble for line-spacing upon said second frame to move to and away from printing position, a second platen also mounted upon said second frame, so that either platen moves to printing position as the other moves away therefrom, means for guiding and feeding work sheets around the first platen, means for 85 guiding work-sheets to coöperate with either of said platens, the last-mentioned means including an introductory guide fixed upon the first frame and extending from the rear downwardly and forwardly and under the second platen and up forwardly thereof, and also comprising a feeding couple upon the first frame at the delivery side of the machine, and means upon said second frame for retaining upon the revoluble platen a record sheet while another sheet is being removed or positioned over said record sheet.
89. The combination with a platen revoluble for line-spacing and having sheet-feeding means, of a frame upon which said platen is movable to and away from the printing point, a support for said frame, sheet-guiding means upon said movable frame and extending from the rear beneath said platen to the front thereof, a second platen below 95 said sheet-guiding means and mounted upon said movable frame to move to the printing point as the revoluble platen moves away therefrom, means upon said movable frame for retaining a sheet upon said revoluble 100 platen while another sheet is advanced thereover, and means upon said support for guiding and feeding a work-sheet to coöperate 105 with either platen.
90. The combination of a platen revoluble 110 for line-spacing, a frame upon which said platen is movable to and away from the printing point, a device above said platen upon which to register the sheets preparatory to a typing operation, means upon said 115 frame to retain a record sheet in place upon said platen while another sheet is advanced thereover upon said platen, and a second platen below the first, said second platen also movable to and away from the printing 120
- 125
- 130

- point, and releasable means for feeding an outer sheet for coöperation with either platen, said feeding means in proximity to said registering device.
91. The combination with a frame, of a sheet-registering table thereon, a second frame, a plurality of platens supported one above another upon said second frame for movement into and out of printing positions, means for feeding an inner sheet around one of said platens, means upon said second frame for retaining a second sheet while another sheet is advanced thereover upon the last-mentioned platen, and means for supporting and guiding an outer sheet to position for coöperation with either platen, said registering table in position to register both the inner and outer sheets.
92. The combination of a sheet-registering or collating table, a revoluble line-spacing platen below said table, a second platen below the revoluble platen, said platens mounted for up-and-down movements to and from printing positions, means coöoperating with the upper platen to feed sheets around the same, means also associated with the upper platen for detaining a sheet in place thereon while another sheet is withdrawn or replaced thereover, and means for supporting and guiding an outer sheet to position for coöperation with either platen, including both sheet-guiding means below the lower platen, and sheet-controlling means above the upper platen in proximity to said table, whereby both inner and outer sheets may be separately registered or collated upon the table while a record sheet is detained upon the upper platen.
93. The combination with superposed or tandem platens movable broadside into and out of printing positions, of means for feeding sheets around one of said platens, means associated with such sheet-feeding platen for retaining a record sheet thereon while another sheet is moved thereover, means dependent upon the movement of the sheet-feeding platen between printing and ineffective positions, for automatically line-feeding the sheets thereon, and means for supporting and guiding a sheet to coöperate with whichever platen is in printing position.
94. The combination with superposed or tandem platens movable broadside into and out of printing positions, of means for feeding sheets around one of said platens, means associated with such sheet-feeding platen for retaining a record sheet thereon while another sheet is moved thereover, means dependent upon the movement of the sheet-feeding platen between printing and ineffective positions, for automatically line-feeding the sheets thereon, means for supporting and guiding a sheet to coöperate with whichever platen is in printing position, and means for disabling said automatic line-feeding means.
95. The combination with two platens mounted one above another for up-and-down movements into and out of printing position, and means for supporting and feeding a work-sheet to coöperate with whichever platen is in printing position, one of said platens being revoluble, of a line-space handle, a pawl-and-ratchet wheel driven thereby, a detent for said ratchet wheel, a pinion driven by said ratchet wheel, a gear on said revoluble platen meshing with said pinion and disengageable therefrom when the revoluble platen moves out of printing position, and a detent device to move with said platen to prevent accidental rotation thereof while the platen gear is out of mesh with said pinion.
96. The combination with a platen frame, of a second frame hinged thereon, a plurality of platens one above the other mounted upon said second frame, whereby either platen may be brought to printing position, a rest for said hinged frame when one platen is in printing position, and a releasable latch to detain said second frame when the other platen is in printing position.
97. In a typewriting machine, the combination with a traveling carriage, comprising a revoluble platen and a paper-table behind the platen, of feed rolls adapted to run upon the platen to cause work-sheets to advance with the turning of the platen, a fixed member in the carriage behind the platen and above the table, a collating table at the front of the platen, means for casting off said rolls to enable work-sheets to be collated upon the table, and a seizing member made effective by said casting off means to hold an inner work-sheet against the fixed member while the outer sheets are being collated upon the table.
98. In a typewriting machine, the combination with a traveling carriage, comprising a revoluble platen and a paper-table behind the platen, of feed rolls adapted to run upon the platen to cause work-sheets to advance with the turning of the platen, a fixed member in the carriage behind the platen and above the table, a collating table at the front of the platen adapted to allow an inner sheet to pass beneath it and outer sheets to rest upon it to be collated, a frame for said rolls, a finger-piece for moving the frame to cast off said rolls to enable work-sheets to be collated upon the table, and a finger connected to the frame adapted to seize the inner work-sheet against the fixed member when the finger-piece is operated.
